CLAIM

The ornamental design for a personal care device, as shown and described.

DESCRIPTION

FIG. 1 is a frontal perspective view of a personal care device showing our new design;

FIG. 2 is a front elevational view thereof;

FIG. 3 is a right side elevational view thereof, of which the left side is a mirror image;

FIG. 4 is a rear elevational view thereof;

FIG. 5 is a top plan view thereof; and,

FIG. 6 is a bottom plan view thereof.

The broken lines in the drawings are included for the purpose of illustration and form no part of the claimed design.
